CLAIM

The ornamental design for a modular pod, as shown and described.

DESCRIPTION

FIG. 1 is a top view of a modular pod showing our new design, with the doors shown open;

FIG. 2 is a top view thereof; with the doors shown closed;

FIG. 3 is a front view thereof; with the doors shown closed;

FIG. 4 is a left view thereof; with the doors shown closed thereof;

FIG. 5 is a rear view thereof; with the doors shown closed;

FIG. 6 is a right view thereof; with the doors shown closed;

FIG. 7 is a top front perspective view thereof; with the doors shown open;

FIG. 8 is a top front perspective view thereof; with the doors shown closed;

FIG. 9 is a left, rear and top perspective view thereof; with the doors shown open;

FIG. 10 is a left, rear and top perspective view thereof; with the doors shown closed;

FIG. 11 is a right, rear and top perspective view thereof; with the doors shown open; and,

FIG. 12 is a right, rear and top perspective view thereof; with the doors shown closed.
